L. C. STRAIT

HYDROCARBON OIL BURNER

Filed Feb. 4, 1927

Patented Aug. 16, 1927.

UNITED STATES PATENT OFFICE.

LACELLE C. STRAIT, OF SACRAMENTO, CALIFORNIA, ASSIGNOR TO THE STRAIT HYDRO CARBON OIL BURNER COMPANY, OF SACRAMENTO, CALIFORNIA, A COPARTNERSHIP.

HYDROCARBON OIL BURNER.

Application filed February 4, 1927. Serial No. 165,859.

This invention relates to improvements in oil or other hydrocarbon burning apparatus, and especially to a system for feeding the oil to the burner. The present invention also particularly represents improvements over the system shown in Patent No. 760,818, dated May 24th, 1904, to Lacelle J. Strait.

This previous system contemplated, among other features, maintaining a certain amount of oil under pressure previous to said oil being fed to the burner, by means of steam from the boiler in connection with which the burner was used; so that the oil would be forcefully fed to the burner at a pressure proportionate to that of the steam.

I have discovered from experiments with said system, however, that under certain conditions, as when operating with a low head or pressure of steam (as is frequently done in the boilers of some industrial plants), an excessive condensation of the steam took place when coming in contact with the cold oil in the float chamber of the system, and as a result the oil as fed to the burner was sometimes mixed with water, which of course caused faulty combustion.

The principal object of the present invention therefore is to provide additional features for incorporation with the previous system, by means of which a certain quantity of oil will be constantly subjected to the desired steam pressure without the danger of excessive condensation of the steam taking place, such as would cause an oil and water mixture to be obtained. At the same time the oil is also heated to a certain extent so that it will more readily volatilize when combined with the steam in the burner.

A further object of the invention is to provide a simple and inexpensive device and yet one which will be exceedingly effective for the purpose for which it is designed.

These objects I accomplish by means of such structure and relative arrangement of parts as will fully appear by a perusal of the following specification and claims.

The figure on the drawing is a side elevation of my improved apparatus shown in section.

Referring now more particularly to the

characters of reference on the drawing, the numeral 1 denotes a closed tank or the like into which the oil is fed from a main source of supply by means of a steam pump 2. The steam pipe 3 from the boiler 4 leads to the steam cylinder of the pump, a valve 5 controlled by a float 6 in the tank governing the feed of the steam to the pump according to the level of oil in the tank. A steam pipe 7 also leads from the boiler to the tank and terminates therein, a regulating valve 8 of an automatic nature of the general type such as is shown in said patent, being preferably interposed in said pipe 7 outside the tank.

Thus far the apparatus described in the same as in the previous patent, but in said patent the oil discharge pipe 9 from the tank was arranged to lead directly to the burner 10 in the firebox of the boiler; while the discharge steam pipe 11 from the top of the tank also leads direct to the burner. This was the arrangement which proved unsatisfactory in service and which I have changed. The discharge pipe 9 which is connected with the tank 1 a short distance below the oil level now leads to adjacent the bottom of a vertical tank 12 separated from the tank 1, the oil of course remaining therein at substantially the same level as in said tank 1. The steam pipe 11 leads down into the tank 12 from the top thereof and discharges at its lower end into a surrounding open topped cylinder 13 which is disposed in the tank preferably in concentric relation therewith and with the pipe. This cylinder is closed on the bottom and its top is above the oil level so that no oil will ever get into said cylinder, while the steam issuing from the pipe 11 is free to leave the cylinder from the upper end. The return or discharge steam pipe 14 from the top of the tank 12 leads to the burner 10, while the oil discharge pipe 15 leads from the side of the tank 12 a certain distance below the normal oil level therein to the burner. The tank 12 is also provided with a draw-off pipe 16 at the bottom.

In operation it will be seen that steam entering the tank 1 and engaging the cold oil therein imparts a certain amount of heat to the oil, but in so doing will be subjected to a great cooling influence tending to induce considerable condensation. This condensed steam drops through the oil in the tank and

will settle at the bottom thereof from where as before it may be drained off through a cock 17. The steam at practically the same pressure then passes to the tank 12 through the pipe 11, where it impinges against and heats the walls of the cylinder 13. This heat is imparted to the oil in said tank, but no great condensation of the steam will now result, since the oil is already somewhat heated before entering this tank. The steam issuing from the top of the cylinder and passing into the return pipe 14 is therefore in a fairly dry condition so that very little moisture of condensation is formed in the tank area above the oil to contaminate the same. Such condensation as is formed from the steam will take place when the steam engages the cylinder walls and before it issues from the cylinder, and the moisture will be confined in said cylinder, from which it may be drawn off when necessary through a bottom drain pipe 18. The oil passing to the burner through the pipe 15 is therefore in a clean and heated condition, while being still acted on by the steam pressure to cause it to be forcefully fed to the burner.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not

form a departure from the spirit of the invention, as defined by the appended claims.

Having thus described my invention what I claim as new and useful and desire to secure by Letters Patent is:

1. A fuel feeding system for an oil burner including a tank, means for feeding oil into the tank, a steam pipe leading into the tank to bear against and impart heat to the oil therein, another tank, oil passage means between the tanks, a steam pipe leading into the second named tank from the first named tank, a chamber in the second named tank into which the steam pipe therein discharges, said chamber being closed on the bottom and open on top above the oil level, an oil burner, an oil pipe leading from the second named tank to the burner, and a steam pipe leading from the top of said second named tank to the burner.

2. In a fuel feeding system for an oil burner, a tank, means for feeding oil thereto and maintaining such oil at a predetermined level, a steam pipe leading into said tank, a chamber in the tank into which the steam pipe discharges, said chamber being closed on the bottom and open on the top above the level of the oil, an oil pipe leading from said tank, and a steam pipe likewise leading therefrom, said last named pipes being arranged for connection to an oil burner.

In testimony whereof I affix my signature.

LACELLE C. STRAIT.
